UNITED STATES PATENT OFFICE.

WILLIAM W. KAY, OF ST. LOUIS, MISSOURI.

CHECK-HOLDER.

1,169,162.

Specification of Letters Patent. Patented Jan. 25, 1916.

Application filed February 11, 1914. Serial No. 818,062.

To all whom it may concern:

Be it known that I, WILLIAM W. KAY, a citizen of the United States, residing at St. Louis, Missouri, have invented a certain new and useful Improvement in Check-Holders, of which the following is a full, clear, and exact description, such as will enable others skilled in the art to which it appertains to make and use the same.

10 This invention relates to check holders that are used by railway companies for holding checks issued as receipts for tickets or other forms of transportation.

15 In my prior Reissue Patent No. 13,373, reissued Feb. 27, 1912, I have described a system for collecting railway transportation which provides for the issuance of a receipt or check to each passenger from whom transportation is collected, said receipt or check being provided with means which identifies it or connects it with the particular ticket or other evidence of transportation for which it was issued, and also with means which designates the passenger's 20 destination. In the system described in my said prior patent the receipt or check that the conductor issued to the passenger was intended to be placed in the passenger's hat or stuck in the back of the seat occupied by the passenger so as to facilitate the checking-up of a train by the auditor, assist the conductor in collecting transportation from all the passengers, and also serve as a receipt for the passenger in case of a 25 dispute as to his destination or as to the particular ticket or other evidence of transportation that he turned over to the conductor.

30 Experience has shown that while a system of the kind described in my said prior patent is efficient in eliminating dishonesty on the part of the conductors, it does not eliminate the liability of a conductor overlooking a passenger from whom transportation 35 has not been received; it does not entirely eliminate the possibility of error or confusion in checking up a train; and it does not insure the return to the conductor of the receipts or checks that he has issued in case the railway company desires or requires that the conductor collect the receipts after the passengers have arrived at their destination.

35 The main object of my present invention is to provide a holder that will reduce to a minimum the possibility of the conductor

overlooking a passenger from whom he has not collected transportation, by insuring the return to the conductor of all the receipts or checks that have been issued to passengers, and by reducing the liability of error or confusion in checking up a train.

Another object is to provide means for preventing a dishonest passenger from altering a receipt or identification check that was given to him when his transportation was collected, or from obtaining possession of another passenger's receipt or identification check.

Figure 1 is a side elevational view of a portion of the inside of a railway passenger coach provided with check holders constructed in accordance with my invention; Fig. 2 is an enlarged front elevational view of one of said check holders. Fig. 3 is a vertical sectional view taken on the line 3—3 of Fig. 2; and Fig. 4 is a rear elevational view of the device shown in Fig. 2.

Referring to Fig. 1 of the drawings, A designates the seats of a railway passenger coach, and B designates devices that are arranged in proximity to said seats for receiving and holding identification checks or receipts that are issued to the occupants of the seats. The devices B can be arranged in any suitable position, and while I have herein shown them mounted on the panels C of the side wall of the car that are located between the windows in the side wall, I do not wish it to be understood that it is essential that the check-holders be arranged in this exact position; nor do I wish it to be understood that my invention is limited to the use of any particular kind of devices for receiving and holding the receipts or identification checks so long as said devices are constructed in such a manner that the passengers or any one except the conductor or an authorized employee of the railway company cannot remove the checks after they have been deposited in said devices.

When the conductor collects a ticket or other form of transportation from a passenger, he places a receipt or identification check *x* in the check-holder B adjacent the seat A occupied by the passenger, as shown in dotted lines in Fig. 2. This check or receipt *x* is provided with a number, symbol or any other suitable means *y* that designates the particular station which is the passenger's destination, and it is preferably provided with a means *z* such, for example,

as a serial number that has been placed on the ticket, which identifies the check or connects it with the particular ticket or evidence of transportation for which it was issued. Just before the passenger reaches his destination the conductor or one of his assistants removes the check from the holder and notifies the passenger that the next station is the passenger's destination.

10 The check-holders B may be constructed in various ways, but it is essential that they be so constructed that the passengers or unauthorized persons cannot remove the checks therefrom. In the form illustrated in Figs. 15 1 to 4, inclusive, each check-holder is provided with a movable portion or door 1 that is provided with side walls or flanges 2 whose longitudinal edges bear against a face-plate 3 to which the lower end of the door is pivotally connected, thus forming an oblong-shaped receptacle when the door is in its closed position, as shown in full lines in Fig. 3. The bottom of said receptacle is formed by a part 4 on the door which is 20 connected to the side walls or flanges 2 thereof, and at the upper end of said receptacle is a contracted mouth or chute 5 produced by bending portions of the front wall of the door and of the face-plate 3 inwardly 25 so as to form chute portions 1^a and 3^a, as shown in Fig. 3. The door is preferably provided with a glass panel 6 and the lower edge of the door is pivotally connected to the face-plate 3 by means of a pintle pin 7 30 that passes transversely through perforated ears 8 on the door and ears 9 on a plate 10 which is secured to the inner side of the face-plate 3, as shown in Fig. 4. A coiled spring 11 that is mounted on said pintle pin 40 normally exerts pressure on the door 1 in a direction to move it outwardly, as indicated by the broken lines in Fig. 3, whenever the door is unlocked. Hooks 12 on the side flanges 2 of the door project inwardly 45 through openings in the face-plate 3 so as to coöperate with a vertically reciprocating latch 13 that is normally held in engagement with said hooks by means of coiled contractile springs 14, as shown in Fig. 4, whose 50 upper ends are connected to stationary studs 15 on the inside of the face-plate 3, and whose lower ends are connected to lugs 15^a on the latch 13. The latch 13 is guided vertically by headed studs 16 on the inner side 55 of the face-plate 3 that project through elongated slots 16^a in said latch, and means is employed for moving the latch 13 downwardly so as to disengage it from the hooks 12 and thus permit the door 1 to open or be 60 opened when it is desired to remove the receipt or identification check from the holder. The means herein shown for moving the latch 13 into an inoperative position consists of a key-operated, rotatable member 17 65 that is provided with a flat surface 17^a which

normally bears upon the upper edge of the latch 13, and also provided with a cylindrical-shaped portion or cam 17^b which engages the upper edge of the latch and moves it downwardly when said member 17 is rotated. The member 17 is rotatably mounted on a boss 18 that projects inwardly from the face-plate 3 and which surrounds a key-opening 19 in said face-plate, and at the inner end of the cylindrical-shaped portion 70 of said member 17 is a flange in which one or more notches 17^d are formed. A plate 20 that is arranged inside of the face-plate 3 and permanently connected to same, is provided with a stud 21 which projects forwardly through the cylindrical-shaped portion of the member 17 and through the key-opening 19 in the face-plate so as to prevent the member 17 from being rotated by means 75 of a knife blade or similar device in general use that could be inserted in the notches 17^d in same, thus necessitating the use of a tubular-shaped key D provided with prongs or lugs 21^a that fit in the notches 17^d in the member 17. A spring 22 arranged inside 80 of the face-plate 3 and connected to the latch-operating member 17, normally holds said member in such a position that the flat or straight surface 17^a thereon bears upon the upper edge of the latch 13. The face-plate 3 is provided with a right-angularly-disposed flange 23 extending around the edge of same and bearing against the side wall panel C of the car so as to form a 85 housing for the latch and other movable parts that are arranged under the face-plate, and, if desired, the face-plate can be provided with two movable portions or doors 1, as herein shown so as to form two check-holders in a single device that can be easily 90 attached to the side wall of the car or to any other suitable part of the car by means of screws 24, as shown in Fig. 2, thus providing separate check-holders for the two occupants of the car seat.

95 A check holder of the construction above-described presents a neat and ornamental appearance and can be manufactured at a very low cost, owing to the fact that most of the parts of same can be stamped out of sheet metal; it effectively locks a check in position and still permits it to be seen by the conductor or auditor who is checking up the train, and it is so designed that the check 100 can be removed from same easily when the door or movable portion is unlocked.

105 In a system employing check holders of the character described the possibility of a conductor overlooking a passenger from whom he has not collected a ticket or some other form of transportation, is reduced to a minimum, owing to the fact that a receipt or identification check is issued for each 110 piece of transportation that is collected and is placed inside of a locked receptacle or 115

holder that is arranged in proximity to the seat occupied by the passenger from whom the transportation is collected. In other words, when the conductor goes through the 5 coach to collect the transportation of the passengers who boarded the train at the last station at which the train stopped, he can tell at a glance the passengers from whom transportation has not been collected, owing 10 to the fact that the checks or receipts that have been issued to passengers who have surrendered their transportation, are located in a conspicuous position in locked devices that can be opened only by the conductor or 15 one of his assistants. There is no possibility of the passengers' identification checks blowing out of the window of the coach or becoming lost, and there is very little liability of error or confusion when an auditor 20 checks up the train, owing to the fact that all of the identification checks or receipts that have been issued can be easily seen by the auditor. If the conductor requests transportation from a passenger who has 25 changed his seat, the passenger can simply designate the seat which he occupied when his identification check or receipt was issued, and if another passenger has occupied the seat in the meantime and the conductor is in 30 doubt as to the honesty of the passenger he can request him to describe the ticket or evidence of transportation that he gave up, the passenger's description being verified or disproved by referring to the ticket now in 35 the possession of the conductor which bears the same serial number or identifying means $\approx$ that appears on the check in dispute.

In addition to furnishing the trainmen facilities for collecting tickets or other 40 forms of transportation rapidly and without liability of overlooking a passenger, my improved check holder eliminates the loss of receipts or identification checks and makes it possible for the conductor to collect all of 45 the checks that have been issued if this is a duty that the railway company requires of the conductor; it overcomes the necessity of the trainmen attempting to keep track of the passengers by memory, or by means of 50 "hat-checks;" and it eliminates annoyance to the passengers by repeatedly asking them to show identification-checks or receipts that have been issued to them, or request the passenger to place his identification check in 55 the band of his hat—a thing which some passengers seriously object to. Furthermore, in a system in which the receipts or identification checks that are issued by the conductor are merely provided with a number 60 or means that indicates the station which is the passenger's destination, my improved check holder makes it impossible for a dis-

honest passenger to alter his identification check or receipt by changing the station number on same, and it also prevents a dishonest passenger from stealing or obtaining possession of a receipt or identification check that has been issued to another passenger.

Having thus described my invention, 70 what I claim as new and desire to secure by Letters Patent is:

1. A check-holder comprising a base portion, a movable portion hinged thereon that coöperates with said base portion to form 75 a receptacle for a check, coöperating parts on said portions that form a chute, and a key-controlled means for locking said movable portion in its closed position.

2. A check-holder comprising a face-plate 80 provided with a hinged member that forms part of a check receptacle, said plate and member having coöperating chute portions, a boss on said face-plate surrounding a key-opening, a locking device arranged on 85 the under side of said face-plate for locking said hinged member in its closed position, and a key-actuated element rotatably mounted on the boss on the face-plate and adapted to move said locking device into an 90 inoperative position.

3. A check-holder comprising a face-plate provided with a movable member that forms part of a check receptacle, coöperating portions on said face-plate and member that constitute a receiving chute, a boss on said face-plate surrounding a key-opening, a locking device arranged on the under side of said face-plate for locking said movable member in its closed position, a key-actuated element 100 rotatably mounted on the boss on the face-plate and adapted to move said locking device into an inoperative position, and a cylindrical stud that extends through said boss so as to necessitate the use of a tubular 105 key.

4. A check-holder comprising a face-plate provided at its edge with an angularly-disposed flange, a door hinged to said face-plate and provided with side flanges that 110 bear against the face-plate, said door and face-plate being provided with coöperating portions that form a contracted receiving chute for the check that is introduced into the holder, and means arranged under the 115 face-plate for locking said door in its closed position.

In testimony whereof I hereunto affix my signature in the presence of two witnesses, this sixth day of February, 1914.

WILLIAM W. KAY.
